UNITED STATES PATENT OFFICE.

STANLEY GISZCZYNSKI, OF PHILADELPHIA, PENNSYLVANIA.

UMBRELLA RUNNER.

Application filed August 30, 1926. Serial No. 132,558.

This invention relates to improvements in umbrella runners, and particularly to a runner structure which combines oppositely disposed clamping means, adapted to releasably 5 clamp the rod of an umbrella simultaneously and prevent the movement thereof on the rod, either when the umbrella is in an open or closed position.

The principal object of the invention is 10 to provide an umbrella runner, which will eliminate the usual spring influenced catches provided on an umbrella rod, for holding the ribs and runner therefor, either in an open or closed position, and further to 15 provide means for effectively clamping and releasing the improved umbrella runner with a minimum of effort.

A further object of the invention is to 20 provide an umbrella runner as specified, which will automatically clamp itself to an umbrella rod, and prevent the movement of the runner thereon in either direction, until it is released by the operation of the 25 push-pull releasing mechanism associated therewith.

Other objects of the invention will appear in the following detail description and in the accompanying drawing, wherein:

Figure 1 is an elevational view of the 30 improved umbrella runner disposed on a rod therefor and showing the relation of the umbrella ribs and stretchers, thereto, in dotted lines.

Figure 2 is a vertical sectional view 35 through the assembled umbrella runner per se.

Figure 3 is a bottom plan view of the 40 improved runner per se, illustrating in dotted lines, the manner of grasping the releasing means associated with the runner.

Figure 4 is an enlarged top plan of one of the clutch members per se.

Figure 5 is an enlarged elevational view 45 of the same.

Referring more particularly to the drawing, the improved umbrella runner comprises a body member 10, which is provided on its exterior, and intermediate its ends, with a grooved annular flange 11, which is suitably 50 slotted about the periphery thereof, to receive a plurality of umbrella rib stretchers as indicated at 12, in Fig. 1, of the drawing.

The body member 10, is further provided 55 with a relatively large bore 13, which extends inwardly from each end, towards the center thereof, and with the inner ends of

the bore tapered or inclined at a point intermediate the ends of the body 10, to form inclined walls 14, and terminating in a relatively small bore or opening 15, concentric 60 with the bores indicated at 13, for slidably receiving the umbrella rod 16, as clearly shown in Figure 2, of the drawing.

The bore 13, which extends inwardly from each end of the body member 10, is threaded 65 to receive a ring nut 17, which is provided on each of a pair of clutch members 18, for retaining the said members in the body member 10, in oppositely disposed axial alignment.

A suitable compression spring 19, is carried by each of the clutch members 18, between the tapered heads 20, thereof and the ring nut 17, which is rotatably retained on the upper end of the clutch members 18, 75 adjacent to the lower gripping member 21, which is carried by one of the clutch members, and with a push rod disc 22, carried by the upper or opposite clutch member 18.

The tapered heads 20, forming a part of 80 the clutch members 18, are provided with a plurality of spaced balls 23, which are disposed in suitable apertures therefor, in the periphery of the said heads, and adapted to normally bear on the umbrella rod 16, and 85 on the inclined walls 14, forming the inner ends of the bores 13, in the body member 10. Said balls are adapted to clamp the rod 16, which extends thru the clutch members 18, by reason of the pressure of the springs 90 19, carried on the shanks of the members 18, and adapted to urge the said members towards each other and to the transverse center of the body member 10.

In order to release or draw the clutch 95 members 18, away from the inclined walls 14, formed within the body member 10, simultaneously, against the tension of the springs 19, a push rod 24, secured to the upper disc 22, is extended downwardly adjacent to the outer wall of the body member 10, thru an alignment aperture 25, which is provided therefor in the annular flange 11, into and thru a second aperture 26, therefor in the lower gripping member 21, and with 100 the depending free end thereof provided with a suitable push button 27.

In releasing the improved runner for 110 slideable movement on the umbrella rod 16, the second and third finger of the right hand are placed on the laterally and oppositely disposed projections 28, formed on the grip-

ping member 21, with the thumb of the same hand in position on the push button 27. Pushing upwardly with the thumb, causes the push rod 24, to partially withdraw and release the upper clutch member out of the bore 13, in the body member 10, simultaneously with a downward pull on the gripping member 21, partially withdrawing the lower clutch member from the opposite end of the bore 13, in the body 10, thereby releasing the balls 23, out of contact with the inclined walls 14, and the umbrella rod 16, and thereby permitting the improved runner to be moved on the rod 16, to an open or closed position.

From the foregoing, it will be readily apparent that I have provided a simple, neat and efficient device for holding an umbrella and in an open or closed position and which may be released with a minimum of effort, since the usual spring catches provided on an umbrella rod are entirely eliminated.

Having thus described my invention, what I claim is:

1. The combination with an umbrella rod including the ribs and stretchers therefor, of a tubular runner, means carried by said runner for pivotally receiving said stretchers, a pair of oppositely disposed friction clutch members positioned in said runner in axial alignment and adapted for receiving an umbrella rod therethru, means provided at each end of said runner for adjustably retaining said clutch members therein, in frictional engagement with said umbrella rod, and co-operative gripping means associated with said runner for simultaneously releasing said clutch members out of frictional engagement with said rod upon the compression of said gripping means.

2. The combination with an umbrella rod including the ribs and stretchers therefor, of a tubular runner, means carried by said runner intermediate its ends for pivotally receiving said stretchers, a pair of oppositely disposed spring influenced friction clutch members positioned in said runner in axial alignment and adapted for receiving said umbrella rod therethru, means provided at each end of said runner for adjustably retaining said clutch members therein, in normal frictional engagement with said rod, means for connecting a pair of co-operative

gripping members with the outer ends of said clutch members, for the simultaneous releasing thereof upon the operation of said gripping members.

3. The combination with an umbrella rod including the ribs and stretchers therefor, of a tubular runner, means disposed about said runner intermediate its ends for pivotally anchoring said stretchers thereto, oppositely disposed inclined surfaces formed in said tubular runner, a pair of oppositely disposed spring influenced clutch members positioned in said runner in axial alignment and adapted for receiving an umbrella rod therethrough, when released, means carried by the inner ends of said clutch members for frictional engagement on said rod upon contact of said inner ends on said inclined surfaces, and a pair of co-operative gripping members associated with said runner and connecting said clutch members, for simultaneously releasing said clutch members out of contact with the inclined surfaces formed in said runner, to permit slidable movement thereof on said rod.

4. The combination with an umbrella rod including the ribs and stretchers therefor, of a tubular runner, a grooved and slotted annular flange carried by said runner intermediate its ends for pivotally receiving the lower ends of said stretchers, oppositely disposed inclined surfaces formed in the bore of said runner intermediate its ends, a pair of oppositely disposed tubular clutch members positioned in said runner from each end thereof and retained therein in axial alignment by a pair of collars threadably inserted in the ends of said runner, an inclined head formed on the inner end of each of said clutch members, a compression spring carried by each of said clutch members between the said collars and inclined heads, a plurality of balls disposed in the periphery of said inclined heads adapted to normally bear on said rod and inclined surfaces in the bore of said runner, and a pair of co-operative gripping members carried by said runner and connecting the outer end of said clutch members, for simultaneously releasing said members and runner for slidable movement on said umbrella rod.

In testimony whereof I affix my signature.
STANLEY GISZCZYNSKI.
